UNITED STATES PATENT OFFICE.

JOSEPH H. BECHTOLD, OF SIOUX FALLS, SOUTH DAKOTA.

CUFF-BUTTON.

1,336,880.

Specification of Letters Patent. Patented Apr. 13, 1920.

Application filed February 2, 1920. Serial No. 355,804.

To all whom it may concern:

Be it known that I, JOSEPH H. BECHTOLD, a citizen of the United States, residing at Sioux Falls, in the county of Minnehaha and State of South Dakota, have invented 5 certain new and useful Improvements in Cuff-Buttons, of which the following is a specification.

This invention relates to certain new and 10 useful improvements in cuff buttons and the primary object thereof is to provide an attachment which can be applied to one end of the shank of a button having rigid heads so as to easily and quickly convert the but- 15 ton into one having a hinged head.

Briefly, the invention proposes to provide jewelers with attachments embodying a short sleeve open at one end and carrying a hinged head on the opposite end whereby 20 the jeweler simply cuts off a head from the shank of a rigid type of button and then slips the open end of the sleeve over the shank and welds same to the latter, whereby to effect the conversion from a rigid 25 to a hinged type of button head.

In the drawings:—

Figure 1, is a top plan view of the invention:

Fig. 2, is a rear side elevation:

Fig. 3, is a section on line 3—3 of Fig. 1: 30 Fig. 4, is a section on line 4—4 of Fig. 1, and

Fig. 5, is a view similar to Fig. 1, on a reduced scale of a rigid head type of button 35 before its conversion in accordance with this invention.

In proceeding in accordance with the present invention a short sleeve or socket 1, is employed which is formed open at its 40 end and the outer end 1' of which is closed and formed with a complete eye or loop 2, the latter preferably integral with the sleeve. A head 3 is provided with a knuckle 4 inter- 45 engaged with the eye or loop 2, so that a hinged connection is formed between the head and the sleeve.

It will be understood from Fig. 5, that the shank S of the rigid type of button there- 50 in shown is cut off at about the line L, fol- lowing which the sleeve 1, is slipped over the end of the shank S and welded, or sol- dered or otherwise rigidly secured thereto.

The invention thus provides an easy, 55 quick and simple, as well as economical manner, of applying the hinged head in place of the rigid head of a button to convert the latter into a hinged head type.

Obviously, the sleeves may be of varying 60 cross-sections as concerns their bores or in- teriors so as to fit shanks of varying cross- sections. The closed end 1', further acts 65 as a wall which abuts the cut end of the shank S, and limits movement of the sleeve or socket 1, on the shank in addition to as- sisting in rigidly and effectively holding the sleeve on the shank.

What is claimed is:

1. An attachment for converting rigid 70 head cuff buttons into the hinged head type, including a sleeve open at its inner end and adapted to be received over and rigidly at- 75 tached to the shank of a cuff button, an eye on the outer end of the sleeve integral there- with, and a head having a knuckle inter- engaged with the eye.

2. An attachment for converting rigid 80 head cuff buttons into the hinged head type, including a sleeve open at its inner end and adapted to be received over and rigidly at- 85 tached to the shank of a cuff button, and a head hingedly connected to the outer end of the sleeve.

3. An attachment for converting rigid 85 head cuff buttons into the hinged type, in- cluding a member formed to engage the shank of the cuff button at the point of re- 90 moval of the rigid head, and a hinged head borne by the member.

In testimony whereof I affix my signature.

JOSEPH H. BECHTOLD.
